FOOTBALL KICKING TEE

Richard E. Cullity, La Mirada, Calif., assignor to W. J. Voit Rubber Corp., a corporation of California

Filed Apr. 17, 1964, Ser. No. 79,538

Term of patent 14 years

(Cl. D34—5)

FIG. 1.

FIG. 2.

FIG. 3.

FIG. 1 is a front perspective view of a football kicking tee showing my new design.

FIG. 2 is a rear perspective view of the kicking tee showing my new design.

FIG. 3 is a side view of the kicking tee, partly in section, taken in a vertical plane passing through the central portion of the kicking tee, the position of this plane being illustrated in FIG. 2 by lines 3—3.

I claim:

The ornamental design for a football kicking tee, substantially as shown.
